DESIGN FOR A COMBINATION BOTTLE AND DOLL COVER THEREFOR

Bertha M. Palmer, Beaverton, Oreg.

Application June 13, 1934, Serial No. 52,162

Term of patent 7 years

To all whom it may concern:

Be it known that I, BERTHA M. PALMER, a citizen of the United States, residing at Beaverton, in the county of Washington and State of Oregon, have invented a new, original, and ornamental Design for a Combination Bottle and Doll Cover Therefor, of which the following is a specification, reference being made to the accompanying drawing, forming a part thereof.

Figure 1 is a front view of a combination bottle and doll cover therefor showing my new design.

Figure 2 is a rear view of the same combination showing my new design.

Figure 3 shows in detail a front view of the bottle which forms a part of the design shown completely in Figures 1 and 2. This figure graphically discloses the flutes which extend along the edges of the body from the base to the mouth.

I claim:

The ornamental design for a combination bottle and doll cover therefor, substantially as shown and described.

BERTHA M. PALMER.
